INVENTOR

Willard C. Foster,
BY
Lucius C. West.
ATTORNEY.

UNITED STATES PATENT OFFICE.

WILLARD C. FOSTER, OF KALAMAZOO, MICHIGAN.

WASHING-MACHINE.

No. 907,766.

Specification of Letters Patent.

Patented Dec. 29, 1908.

Application filed May 9, 1907. Serial No. 372,819.

To all whom it may concern:

Be it known that I, WILLARD C. FOSTER, a citizen of the United States, residing at the city of Kalamazoo, in the county of Kalamazoo, State of Michigan, have invented a new and useful Washing-Machine, of which the following is a specification.

My invention relates to forcing a portion of the wash water through the clothes, as a 10 means of removing the dirt from the clothes, in lieu of scrubbing, or agitating.

The objects of my invention are the mechanical means herein described and claimed, to transfer portions of wash water which is in 15 the machine, onto and through the garments, with ease, speed, force, and volume, and to continue said repetition of the operation of the water a few times until the clothes are clean. Please note this regarding my 20 objects. Everything about my machine increasing the ease, speed, force, and volume of handling water in a given time, onto, and through the clothes, contributes to those objects.

25 In the accompanying drawing forming a part of this specification—Figure 1 is a plan of the washing machine as when being operated; Fig. 2 a plan of the machine with the covers and crank removed; Fig. 3 a side elevation of the machine with parts broken away, and parts in section on dotted line *a—a* in Fig. 2, showing the interior; Fig. 4 a water spout in cross section.

Referring to the parts of the drawing 30 pointed out by numerals, the main tub 5, of the machine may be made of any desirable material. It is open at the top, and sets on the bottom in an upright position when in operation. It has a cover 6, and 7, both of 40 which are used when machine is in operation. The cover 6, forms really a part of the main cover 7, by detachably fitting into a central clothes hole in the main cover. The main cover has a rail 8 on its upper face to attach a clothes wringer to when used. The design is to show that a wringer may be used and not a particular construction for holding it. The tub 5 has handles 9, 10, on the sides at the top to carry it by.

45 Much shorter than the height of the interior of the tub 5, is what, for convenience, I call a basket, 11. The basket is two or three inches, more or less, smaller all around than the interior of the tub 5. The top or upper end of the basket is open, and has no top closure. The basket 11 clears a little

the bottom of the tub 5. It has a bearing in the center of the tub 5, on the inner bottom at 12, in which it revolves easily. It is attached to the shaft 14, the latter having easy 60 bearings in the central hole of the cover 6, when turned by crank 15. Slantingly up and down on the exterior wall of the basket 11, are 8 open spouts 16, separated a little from each other around the basket, between 65 it and the interior wall of the tub 5, one edge being soldered to the wall of the basket 11. The concave portion 17 of the open spout stands out from this to catch the water when the crank is turned as explained in the 70 operation. The number of spouts 16 may vary, their arrangement is shown by top view at 16, and by downward and forward extended portions shown by dotted lines 22 Fig. 2. The free edge of the spouts 16, at 75 20, are turned for stiffening the spouts for handling them, Fig. 4. By referring to Fig. 3 it will be seen by the space below the covers what a freedom there is for the deliver- 80 ance of much water, with great force in here over the clothes, which is forced onto and down through the clothes.

It is shown in Fig. 3 that the side wall of the basket 11 has perforations 18, and in Fig. 2 perforations 19 through the bottom. 85 The idea is to make the basket as much as possible like open skeleton work, like open wire work, so that the dirty water from the clothes will readily mix with the water in the tub 5, and not be retained in the basket 11. 90

In the operation perhaps it is better to fill the basket 11, nearly full of clothes at a time. Fill the tub 5 and basket about even with top of basket with water. Add what- 95 ever soap desired. Then turn the crank 15 first in one direction, then in the other if de- 100 sired, or do the washing by turning in one direction if preferred. The basket turns ex- 105 ceedingly easy, and the effect upon the water is to raise it by the spouts 16, up the side of the basket 11, with great force against the under face of the covers 6, 7, and it reacts down upon and through the clothes. The water has to be lifted by turning the crank, hence by turning the crank briskly the water 110 is necessarily raised with much speed and force. The result is the short time it takes to do a washing, without boiling the clothes, just use hot water, and no damage to the clothes. As many times as the machine has to be filled with clothes in doing a washing 115 refill with clean water.

Having thus described my invention what I claim as new and desire to secure by Letters Patent of the United States is—

1. A washing machine comprising a tub 5 having a central bearing on the bottom thereof, an annular cover to the tub having an annular rim or flange to form a support for the clothes wringer or like device and provided with a central removable cover portion, an open work cylindrical basket adapted to act as a clothes container, a shaft passing through the basket and journaled in the bearing on the bottom of the tub, and concave curved channelled ribs secured at an incline on the exterior walls of the basket the ribs making close engagement with the walls of the tub and having reversed angular edges.

2. A washing machine comprising a tub 20 and a central bearing on the bottom thereof, an annular cover to the tub having a central removable portion, a cylindrical basket in the tub adapted to act as a clothes container, a shaft forming a support for the basket and 25 journaled in the bearing on the bottom of the tub and in the removable portion of the cover, a handle on the upper extended end of the shaft, and concave curved channelled ribs slantingly secured on the exterior walls of the 30 basket, the ribs having angular stiffening edges set at an angle opposite to the channel in the ribs.

3. A washing machine comprising a tub having a center bearing on the bottom 35 thereof, a tight fitting cover to the tub hav-

ing a central removable portion, a broken annular supporting rim on the cover a shaft journaled in the bottom bearing and passing up through the removable portion of the cover, a cylindrical perforated casing carried 40 by the shaft and having an open upper end, and concave curved channelled ribs secured at an incline to the outer walls of the casing, said ribs having overturned angular edges and making close engagement with the walls 45 of the tub.

4. A washing machine comprising a tub having a center bearing on the bottom thereof, a tight fitting cover to the tub having its edge projecting out beyond the rim of 50 the tub engaging the inner wall of the tub and provided with a central removable portion, a shaft journaled in the bottom bearing and passing up through the removable cover portion, a handle on the upper extended end 55 of the shaft, a cylindrical perforated casing supported on the shaft having an open upper end to form a clothes receptacle, and concave curved channelled ribs slantingly secured to the outer walls of the casing, the ribs having 60 reversed angular edges and making close engagement with the walls of the tub the ribs being inclined in a forward direction so that as the cylinder is revolved the water in the tub is elevated.
